UNITED STATES PATENT OFFICE

ROLLA A. MORTON, OF LONG BEACH, CALIFORNIA, ASSIGNOR TO WESTERN WHEELED SCRAPER COMPANY, OF AURORA, ILLINOIS, A CORPORATION OF ILLINOIS

ELEVATOR

Application filed February 12, 1926. Serial No. 87,863.

My invention relates to elevators such as are commonly used on elevating graders, comprising a belt traveling over upper and lower rollers mounted on a suitable frame, and it has to do particularly with elevators in which the belt is caused to travel by power applied to a driving roller supported by the frame at a point removed from the source of power, as for example at the outer or upper end of the frame. In such elevators the roller at the upper end of the frame should be made adjustable longitudinally thereof to take up slack in the belt, and it should also be capable of angular adjustment to some extent to maintain uniformity of tension at the opposite margins of the belt, and the object of my invention is to provide a construction by which such driving roller can be adjusted as necessary without affecting the driving connections by which it is driven from a more or less remote point, such as a motor mounted on the frame of the grader. An example of an elevating grading and loading machine of the type employing an elevator of this character is found in the application of Edward P. Henry and myself, Serial No. 699,860, filed March 17, 1924, but while my present invention is primarily intended for application to an elevating grader of that character, it may also be applied in any other situation for which it is adapted.

The manner in which I accomplish my object will appear from the following description of my invention with reference to the accompanying drawings. What I regard as new is set forth in the claims.

In the drawings,—

Fig. 1 is a plan view of the upper end portion of my improved elevator, some parts being broken away and other parts being shown in longitudinal section;

Fig. 2 is a cross-section on line 2—2 of Fig. 1; and

Fig. 3 is a partial side elevation of the upper end portion of the elevator with the driving connections omitted, showing the arrangement for angularly adjusting the driving roller.

Referring to the drawings,—4, 5 indicate the side members of an elevating frame which

are preferably in the form of parallel channel bars, as best shown in Fig. 2, which may be jointed at their inner ends to permit of vertical adjustment of the outer end portion of the elevator with reference to the inner end portion thereof. Said side members extend down to the lower portion of the machine with which the elevator is associated, and at the lower end of the elevator frame a return roller is provided over which the conveyor belt runs. The connections at the lower end of the elevator frame and the return roller are not shown as they may be of any approved construction.

Mounted upon the side members of the elevator frame to move longitudinally thereof is a transverse support in the form of a frame comprising upper and lower transverse plates 6, 7 arranged respectively above and below the side members 4, 5 and supported by said side members to slide longitudinally thereof, said plates being connected at their ends by vertical plates 8, 9, as best shown in Fig. 2. At the upper and lower ends of the plates 8, 9 are slide blocks 10 that bear on the upper and lower flanges of the side members 4, 5, as shown in Figs. 2 and 3. The blocks 10 engage said side members loosely enough so that the support is capable of a limited amount of angular movement relatively to the side members to permit angular adjustment of the roller hereinafter described for the purpose of adjusting the tension at the side margins of the elevator belt.

The plates 8, 9 extend forward from the cross-plates 6, 7 as shown in Fig. 1, and carry bearing boxes 11, 12, respectively, in which are journaled the ends of a transverse shaft 13 that carries the driving roller 14 over which the upper portion of the elevator belt 15 travels and by which it is driven. As shown in Figs. 1 and 3, the end portions of the shaft 13 extend through longitudinal slots 16, 17 in the outer ends of the side members 4, 5. Preferably the ends of the shaft 13 are mounted in ball bearings 18, 19 fitted in the boxes 11, 12, respectively. At one end, in the illustrated construction the right hand end, the shaft 13 is provided with a bevel gear 20 non-rotatably secured thereto, which gear is

provided with a sleeve-like hub 21 that fits in the ball bearing 19 and forms a journal for that end of the shaft 13. The gear 20 meshes with a bevel gear 22 non-rotatably mounted on a short shaft 23 that extends longitudinally of the elevator frame and is mounted, preferably in ball bearings 24, in a box 25 that is carried by the plate 9 and is fixedly secured in right angular relation to the box 12, so that the axes of the shafts 13 and 23 are at right angles to each other, and the pinion 22 is held constantly in mesh with the gear 20. A housing 26 is preferably provided to enclose the gears 20, 22, the proximate end of the shaft 13 and also the ball bearings 19, 24.

The outer or lower end of the shaft 23 is connected by a universal joint 27 and a telescopic connection 27^a with a drive shaft 28 which extends longitudinally of the elevator frame at one side thereof and is driven from any suitable source of power, such as a motor mounted on the machine with which the elevator is associated. By this arrangement, the shaft 23 may be angularly and longitudinally adjusted relatively to the drive shaft 28, and consequently when the roller 14 is adjusted, either bodily longitudinally of the elevator frame, or angularly relatively thereto, the shaft 23 may either move longitudinally with relation to the drive shaft 28 or angularly relatively thereto as may be necessary to permit of such adjustment of the roller 14 in view of the fixed relation of the shaft 23 to the shaft 13 incident to the connection of the bearing box 25 with the box 12 and the plate 9.

For adjusting the roller 14 bodily longitudinally of the elevator frame I provide a rock shaft 29 mounted on the side members 4, 5, which shaft at one end carries a lever 30 and at the other end is provided with a crank 31. One end of the lever 30 is connected by a connecting rod 32 with a lever on the machine or any other suitable means for rocking the shaft 29. The other end of the lever 30 is connected by links 33, 34 and a turn buckle 35 with the plate 9. In like manner the crank 31 is connected by links 36, 37 and a turn buckle 38 with the plate 8. Obviously by rocking the rock-shaft 29 the lever 30 and crank 31 will be swung in unison, thereby moving the plates 8, 9 in unison longitudinally of the elevator frame and correspondingly adjusting the roller 14. If it be desired to adjust said roller angularly, this may be accomplished by adjusting one or the other of the turn buckles 35, 38. It is not essential that two turn buckles be provided, as the angular adjustment of the roller may be effected if one only be provided, although I prefer to use two.

When the rock-shaft 29 is rocked the support comprising the plates 6, 7 slides longitudinally of the side members 4, 5 of the elevator frame, and as both bearing boxes 11, 12 and also the box 25 are all carried by said sup-

port, the driving connections for the roller 14 are adjusted with it without being in any way affected by such adjustment. The performance of this operation of course involves longitudinal movement of the shaft 23 with relation to the drive shaft 28, but this is permitted by the extensible connection 27^a between said shafts.

So far as I am aware I am the first in the art to provide an elevator with a driving roller adjustable longitudinally of the elevator frame, in connection with driving means, and driving connections between such driving means and the roller that are adjustable longitudinally of the frame with the roller, and I also believe myself to be the first to provide an arrangement of that character which will permit angular adjustment of the roller without disturbing the driving connections. My invention is therefore not limited to the specific construction shown and described, but includes such modifications or variations thereof as would occur to those skilled in the art.

What I claim as my invention and desire to secure by Letters Patent, is—

1. The combination with an elevator frame comprising side members, a transverse support mounted on said side members for adjustment longitudinally thereof, said support comprising a plate extending across the frame below said side members, and a slide block between said plate and each of said side members, of a roller, bearings for said roller, carried by said support, driving means, and driving connections between said driving means and said roller adjustable longitudinally of the frame with said support.

2. The combination with an elevator frame comprising side members, a transverse support mounted on said side members for adjustment angularly relatively thereto, said support comprising plates extending across the frame above and below said side members, and slide blocks between each of said plates and each of said side members, of a roller, bearings for said roller, carried by said support, driving means, and driving connections between said driving means and said roller adjustable with said support when it is angularly adjusted.

3. The combination with an elevator frame, a support mounted thereon and movable longitudinally thereof, a roller, a shaft for said roller, bearings for the end portions of said shaft, carried by said support, a longitudinally disposed shaft mounted in bearings carried by said support, gearing connecting said shafts, and a drive shaft having an extensible connection with said longitudinally disposed shaft.

4. The combination with an elevator frame, a support mounted thereon and movable longitudinally thereof, a roller, a shaft for said roller, bearings for the end portions of said

shaft, carried by said support, a longitudinally disposed shaft mounted in bearings carried by said support, gearing connecting said shafts, and a drive shaft having an extensible and flexible connection with said longitudinally disposed shaft.

5 5. The combination with an elevator frame, of a support mounted thereon and movable longitudinally thereof, a roller carried by said support, a driving gear connected with said roller, a pinion carried by said support and movable therewith, said pinion meshing with said gear for driving said roller, a drive shaft extensibly connected with said pinion for driving the same, and means mounted on the elevator frame and connected with said support, and operable to move the same longitudinally of the elevator frame independently of said drive shaft.

10 6. The combination with an elevator frame, of a support mounted thereon and movable longitudinally thereof, bearings carried by said support, a roller having its end portions mounted in said bearings, a driving gear connected with said roller, a pinion carried by said support and movable therewith, said pinion meshing with said gear for driving said roller, a drive shaft extensibly and flexibly connected with said pinion for driving the same, means mounted on the elevator frame and connected with said support, and operable to move said support longitudinally of the elevator frame, and devices between the latter means and said support operable 15 to angularly adjust said support relatively to the elevator frame.

20 7. The combination with an elevator frame comprising side members, of a transverse support mounted on said side members to move longitudinally thereof, bearings carried by the opposite end portions of said support, a roller having a shaft journaled in said bearings, a longitudinally disposed shaft mounted in bearings carried by said support, gearing 25 connecting said shafts, means operable to adjust said support longitudinally of the elevator frame, and a drive shaft extensibly connected with said longitudinally disposed shaft.

30 8. The combination with an elevator frame comprising side members, of a transverse support mounted on said side members to move longitudinally thereof, bearings carried by the opposite end portions of said support, a 35 roller having a shaft journaled in said bearings, a longitudinally disposed shaft mounted in bearings carried by said support, gearing connecting said shafts, means operable to adjust said support longitudinally of the elevator frame, a driving shaft extensibly and flexibly connected with said longitudinally disposed shaft, and means operable to adjust said support angularly relatively to the elevator frame.
